H. D. TAYLOR.

Car Brake.

No. 8,710.

Patented Feb. 3, 1852.

UNITED STATES PATENT OFFICE.

HY. D. TAYLOR, OF NEWARK, NEW JERSEY.

RUNNING-GEAR OF RAILROAD-CARS.

Specification of Letters Patent No. 8,710, dated February 3, 1852.

To all whom it may concern:

Be it known that I, HENRY DAVIS TAYLOR, of the city of Newark, in the county of Essex and State of New Jersey, have invented certain new and useful improvements in means of preventing locomotives, rail-cars, and all carriages employed on railroads from running or being thrown off the track or rails; and I do hereby declare 10 that the following is a full, clear, and exact description of the same, reference being had to the accompanying drawings, forming part of this specification, in which—

Figure 1 is a longitudinal vertical section 15 of the platform or floor frame and trucks of a rail car having my improvements applied. Fig. 2 is a front elevation of the same. Figs. 3 and 4 are views of some of the parts detached which are more particularly referred to in suitable places in the description.

Suitable letters of reference indicate corresponding parts in each of the several figures.

25 This invention relates to certain means of removing obstructions from the track and preventing the cars, engine or any carriages employed on railroads from being caused to run off the track by any unevenness or obstruction that does not admit of being easily removed or by any other means.

To enable others skilled in the art to make and use my invention I will proceed to describe its construction and operation.

35 A represents the platform or lower frame of the car.

B, B, are trucks; C, C, their axles, and D, D, their wheels. The trucks are constructed and the car supported on them in 40 the usual manner. The cross pieces E, E, on which the car is supported and to which it is secured are arched (see Fig. 2).

F, F, are the rails of the tracks which may be of any suitable form which admits 45 of the inner edge projecting.

Below the car and inside the rails there is a strong frame or truck consisting of longitudinal piers G, G, and crosspieces H, H, of timber or other materials united by metal 50 frames or corner pieces I, I, in each of which frames or corner pieces is hung the axle a, of a small wheel J, which inclines at an angle of about 45° and is provided in its periphery with a groove fitting to the inner edge of the rail about half way between the wheels D, D, in such a manner that when

all of the said wheels J, are in their places the frame can not rise or move upward. This frame with its wheels is represented in Fig. 4 which is a plan of it and is also seen 60 in Fig. 2, and partly in Fig. 3.

Connected to the outer end timber of each truck B, near each side is a rod K, which passes through a guide L, attached to the opposite end timber. To the inner edge of 65 each rod K, a link M, is attached at the center of its length. One end of each link M, is connected by a rod N, at one end to one of the side timbers G, G, of the lower truck or frame and the opposite end of each link by 70 a rod P, to a link O, which hangs at the center of its length on a stationary pin b, attached to the platform A, of the car. This link O, must be hung in such a position as to move freely and allow of the shortening 75 of the distance between the ends of the two links M, which are opposite each other.

Across the center of each truck is placed a framing consisting principally of two parallel bars U, U, and on pivots inserted 80 through these bars are hung links Q, R, R, the pivots passing through the links at about the middle of their length. The front timber of the truck is omitted in Fig. 2 to show these bars U, U. The links Q, are each connected by two rods S, S, (one at each end) 85 to the links R, R; and the opposite ends of the links R, R, to those which are connected to the links Q, are connected by rods T, T to the cross timbers H, H, of the inclined wheel frame. The last described combinations of rods and links connect the trucks 90 B, B, with the lower truck or frame G, G, H, H and confine them together laterally and are precisely the same in their arrangement and operation as the first described 95 combinations, which connect the body of the car and the trucks B, B, with the lower truck or frame and confine them together longitudinally, the links Q performing the same duty 100 as those O, viz, that of allowing for the variation in the distance between the ends of the levers R, R. By means of the two sets of rods and links, one set on each side of the car and one set across each truck B, 105 the car is connected to the lower truck or frame G, G, H, H, in such a manner as to admit of each one, or any number at the same time of the wheels D being raised from the rail in passing over anything which may 110 be upon them and insures their safe return to their proper position on the rail when

they have passed over the obstruction or unevenness of surface without giving any very perceptible shock to the car.

Attached by pins *c*, to the end of the lower truck or frame *G, G, H, H*, there are two guards *V*, one on each side nearly close to the inside of the wheels *D, D*. These consist of frames or bars having a large fork in front which is suspended by a chain *p*, 10 from the truck, holding it just above the surface of the rails, the said fork having a flange *d*, which terminates in a point *e*, at the bottom inside the rails. Stretched across the front or mouth of the fork there is a 15 strong band *l*, of india rubber or any elastic material. This is attached by any secure means. At the back of each fork there is a standing rest *f*, which when the guard is a little raised rests against the axle *C* behind it. The guards *V*, are united by cross stretchers *g, g*, and are designed to catch anything which may be upon the rails and either move it off or carry it along until a 20 convenient time for stopping. The india rubber bands will break the force of the shock to the car, and prevent injury to living creatures. The number of guards may be increased and the elastic bands made to extend all across in a continuous sheet. The 25 front of the engine and each or one end of every car or the outer ends of the first and last cars of a train may be provided with the above guards.

The operation of the improvement is as 30 follows: When the cars or engine are running the guards hang perfectly free, but as soon as they meet with an obstruction they are raised and thrown back by the force of the concussion and the rests *f* bear against 35 the axle *C*. It depends on the nature or form of the obstruction whether it will be thrown off or carried in front. In case it is carried in front the guards will be pre- 40

vented from being thrown back by the axle *C*. Any obstruction of such nature as to 45 adhere to the rails or not to admit of being moved by the guards will be passed over by the wheels *D, D*, but owing to the form and position of the wheels *J, J*, which are prevented from rising and which need not 50 extend far on the rail, they the said wheels *J, J*, will either escape, pass under or remove the obstruction, and as they are confined to the rails and the trucks must always be brought back to the same position on the 55 rails in relation to the wheels *J, J*, the cars can not get off the track.

I do not claim the grooved inclined wheels *J, J*, fitting to the rails in the manner described; but

What I do claim as my invention and desire to secure by Letters Patent, is—

1. The lower truck or frame *G, G, H, H*, supported upon the rails and prevented from rising by grooved inclined wheels *J, J, J, J*, 60 fitting to the edge of the rails, and connected to the trucks, and body of the car by series of links and rods substantially such as are herein described and represented by *O, P, P, M, M, N, N, K, K*, and *Q, S, S, S, R, R, T, T*, operating for the purpose set forth.

2. And I also claim the forked guards *V*, provided with elastic bands *l, l*, and attached to the lower trucks *G, G, H, H*, so 65 as to move up and down freely but formed so as to take a firm bearing or rest on the front axle or any stationary part of the front truck when brought into contact with any obstruction substantially as and for the 70 purpose herein set forth.

HENRY DAVIS TAYLOR.
